CLAIM

We claim the ornamental design for a joystick, as shown and described.

DESCRIPTION

FIG. 1 is a front perspective view of the joystick showing our new design;

FIG. 2 is a top plan view thereof;

FIG. 3 is a left side elevation view thereof;

FIG. 4 is a right side elevation view thereof;

FIG. 5 is a front side elevation view thereof;

FIG. 6 is a back side elevation view thereof;

FIG. 7 is a front perspective view of a second embodiment thereof;

FIG. 8 is a top plan view thereof;

FIG. 9 is a left side elevation view thereof;

FIG. 10 is a right side elevation view thereof;

FIG. 11 is a front side elevation view thereof; and,

FIG. 12 is a back side elevation view thereof.

The bottom side of the joystick design is non-ornamented and not shown, and forms no part of the claimed design.

The broken lines in the FIGURES are for illustrative purposes only and show portions of the joystick, including user interface elements, that form no portion of the claimed design.
